UNITED STATES PATENT OFFICE.

HENRY H. RIGGIN, OF ALTOONA, PENNSYLVANIA.

BLow-OFF VALVE.

No. 806,084.

Specification of Letters Patent.

Patented Sept. 24, 1907.

Application filed December 17, 1906. Serial No. 348,256.

To all whom it may concern:

Be it known that I, HENRY H. RIGGIN, a citizen of the United States, residing at Altoona, in the county of Blair and State of Pennsylvania, have invented certain new and useful improvements in Blow-Off Valves; and I do declare the following to be a full, clear, and exact description of the invention, such as will enable others skilled in the art to which it appertains to make and use the same.

10 This invention relates to blow-off valves for boilers.

The object of the invention is to produce a valve which may be placed at the bottom or leg of a boiler for removing the mud and scales therefrom, and by which the seat is protected from the scales or mud to prevent the cutting out or scoring of the seat and the consequent leaking of the valve.

Figure 1 represents a vertical section of a valve embodying this invention; Fig. 2 represents a top plan view of the valve seat; Fig. 3 represents a detail sectional view, taken on line 3—3 of Fig. 2; Fig. 4 represents a top plan view of the valve; Fig. 5 represents a top plan view of the valve seat protector removed; and Fig. 6 represents a side elevation, partly in section, of the valve stem and seat protecting disk.

25 In the embodiment illustrated, a valve casing or shell 10 is shown having a discharge port 11, provided with an interior screw-thread 11'. A removable valve seat 12 having an exterior screw-thread is screwed in said discharge port 11 and is provided with two ports 13 and 14 for the discharge of the fluid or scales from the boiler. A disk valve 15 having two openings 16 and 17 to register with the openings 13 and 14 in the valve member 12, is rotatably mounted on said valve seat by means of a central stud 18 on its lower face, which fits 35 in a socket 19 in the seat 12. The rotation of said disk a one-quarter turn in either direction, brings the openings 16 and 17 into or out of register with the openings 13 and 14 and opens or closes the valve. When the valve is open, its seat is protected by the disk 15, and 40 therefore no scales or mud can come in contact with said seat during their passage through the openings 13, 14 and 16, 17. The disk is always in place on the seat and hence no mud or scales can enter between it and the seat to wear the parts.

45 A valve stem 20 is longitudinally movable in a tubular extension 25 of the casing 10 and has depending, oppositely-disposed lugs 21 and 22, adapted to extend into slots 16' and 17' in the disk 15 to open and close the valve. This stem 20 has an annular shoulder 23, beveled on its outer face at 24, to engage a corresponding seat 26 on the extension 25 and forming a ground joint. A packing 27 is disposed in the tubular extension 25 around the valve stem 20 and a stuffing-box gland in the form of a nut 28 having an enlarged head 50 29 is secured in said extension above said packing to hold it securely in place.

A guide frame or bracket 30 for the stem 20 is screwed on the outer face of the extension 25 and a stem locking member in the form of a nut 35 is mounted on said guide frame 30. This locking nut 35 engages a shoulder 20' on the valve stem 20 and when the bracket 30 connected with said nut is screwed down on the casing, the nut being in engagement with the shoulder 20' on the stem, forces it down on the valve 15 and holds said valve tightly on its seat. This nut thus controls the stem 20 and when said nut is loose on the stem, the water and steam pressures force the valve 23 against the seat 24, whereby a steam-tight joint is formed, so that the packing gland 28 may be removed and the valve repacked. This is an important feature in a valve. This locking 70 nut 35 is designed for use when filling the boiler through the valve by a hose connection, and the nut is then tightened down on the stem 20, which forces the stem 20 down onto the disk valve 15 and prevents it from leaving its seat while the boiler is being filled, and 75 hence no sediment can get under the valve 15 to score the seat. When steam pressure is on in the boiler, the nut 35 is loosened and the pressure will hold the disk and stem in place and prevent leakage.

A plug 40 is screwed into openings in the casing 10 and is removable to clean out the boiler with a rod. This valve is constructed to withstand the hard service to which such valves are subjected to provide for the making of quick repairs. To repair the valve, the bottom cap is taken off and all of the parts may be removed 85 without disturbing the position of the valve casing in the boiler.

I claim as my invention,—

1. In a blow-off valve the combination of a valve casing having an outlet, a valve seat detachably secured therein and having a central socket and openings therethrough into the outlet, a disk valve revolvably mounted on said seat and having a depending stud to fit in said socket, a valve stem detachably connected with said valve and having a shoulder on its upper end and a lock nut engaging 90 said shoulder and having means for adjustably connecting it with the casing.

2. In a valve, the combination of a valve casing, having an outlet, a valve seat detachably secured therein, and having openings communicating with said outlet, a tubular extension arranged opposite said valve seat, a disk valve rotatably mounted on said seat and having openings therethrough to register with the openings in said seat, a valve stem extending through said tubular extension and having means for detachably engaging said disk valve, 100 and provided with an annular shoulder to engage a seat in said extension, and means under the control of the operator for forcing said valve stem in contact with the valve to hold it tightly on its seat.

In testimony whereof I have hereunto set my hand in 110 presence of two subscribing witnesses.

HENRY H. RIGGIN.
